FIG. 1 is a top plan view of a wash cloth showing my new design.

FIG. 2 is a side elevation of the wash cloth shown in FIG. 1.

FIG. 3 is an end elevation of the wash cloth shown in FIG. 1.

The undisclosed, bottom portion of the washcloth is substantially plain and unornamented.

The dotted lines illustrated in FIG. 1 on the drawing are intended to represent conventional stitching.

I claim:

The ornamental design for a wash cloth, as shown and described.
